(57) **CLAIM**

The ornamental design for a bow-tie, as shown and
described.

DESCRIPTION

FIG. 1 is a front perspective view of the bow-tie, showing
my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in the drawings depict portions of
the bow-tie that forms no part of the claimed design.
